INDIVIDUAL FREEZING CUP WITH ICE RELEASE

Logan L. Mallard, Norfolk, Va.

Application December 4, 1941, Serial No. 421,644

6 Claims. (Cl. 62—108.5)

This invention relates to freezing containers for use in domestic refrigerators, and is particularly concerned with containers of the individual type in contradistinction to the conventional evaporator tray utilizing a grid to divide the tray into a plurality of cube-forming compartments.

An object of the invention is to provide a freezing container having ice-dislodging means of simple construction associated therewith, the entire unit being capable of manufacture on a low-cost production basis.

Another object is to provide individual freezing containers resembling the conventional muffin or cup-cake tin having ice-dislodging means operatively associated therewith but readily separable therefrom, adapting the container for use in making ice cubes or blocks or for baking or other purposes.

A further object is to provide ice-dislodging means of an extremely simple yet highly efficient nature for use with annular containers and which means may be sold as a separate unit for application to a container whenever it is desired to use the latter for freezing liquids.

The foregoing and other objects and advantages will become apparent in view of the following description taken in conjunction with the drawing, wherein:

Fig. 1 is a view in elevation of a container and coating ice-dislodging means in accordance with the invention;

Fig. 2 is a view similar to Fig. 1 but showing the ice-dislodging member removed from the container;

Fig. 3 is a plan view, and

Fig. 4 is a transverse vertical section of Fig. 1;

Fig. 5 is a plan view of a modified form of container;

Fig. 6 is a section on the line 6—6, Fig. 5;

Fig. 7 is an elevation of a further modified type of container; and

Fig. 8 is a perspective of a still further modification.

Referring to the drawing in detail, a container is indicated at 10 and may be of the conventional muffin or cup-cake type having synclinal side walls defining a freezing chamber of rounded contour. Preferably, but not necessarily, the outer surface of the container adjacent the bottom thereof is provided with gripping members 11 to assist in holding the container against rotation when using the ice-dislodging mechanism in a manner hereinafter described. The interior bottom surface of the container is provided with a cam projection 12 which in the form shown in

Figs. 1 to 4, inclusive, consists in indenting the metal of the bottom wall. The top of the container is preferably formed with a bead or flange 13.

5 A container of this type may be made on a low-cost production basis and sold as a cup-cake or muffin tin or for general baking purposes, and when it is desired to use the same for freezing ice cubes from water or other liquids or fluids, ice-dislodging means separable from the container is used. Such means as here shown comprises an annular member or ring 14 having a knurled gripping surface 14', a depending flange 15 and an inwardly projecting flange 16, said flanges lying at substantially right angles to one another to engage the bead 13 and provide bearing means whereby the ring is maintained in proper centered position on the container yet may be freely rotated with respect to the container. 10 The flange 16 is enlarged or projected inwardly as at 17 to form a support for a downwardly projecting finger or stud 18 which is embedded in the ice when the water or other fluid is frozen. 15 The ice-dislodging ring just described is common to all of the different types of containers illustrated in the drawing, the modifications in Figs. 5, 6, 7 and 8 relating to the container rather than to the ring.

20 In Figs. 5 and 6 the projection 12 of the container of Figs. 1 to 4 is substituted by wedge-shaped cam members 20 and 20' which project upwardly into the container and are frozen into the ice when the latter is formed. When the ice block in the container is turned or angularly displaced, the cam members 20 tend to urge the block upwardly, as will be readily understood. 25 The container in these figures is indicated at 10'. The projection 12 of the container of Figs. 1 to 4 is substituted by wedge-shaped cam members 20 and 20' which project upwardly into the container and are frozen into the ice when the latter is formed. When the ice block in the container is turned or angularly displaced, the cam members 20 tend to urge the block upwardly, as will be readily understood. The container in these figures is indicated at 10'.

30 Fig. 7 illustrates a container 10'' having a knurled gripping surface 21 which may consist of a strip of abrasive material cemented on the exterior wall of the container and bearing indicia relating to advertising or any other desired matter. This type of gripping surface is of particular advantage where the containers are given as favors or prizes to advertise certain products.

35 Fig. 8 illustrates a container 10''' having a base 22 formed with a series of radial projections 23 to facilitate gripping of the container.

The manner in which the device operates will 40 be obvious in view of the foregoing description taken in conjunction with the drawing. Whenever it is desired to use the container for making ice blocks or cubes, it is filled with the liquid or other material to be frozen, the ring 14 applied 45 and the entire unit placed in the freezing com-

partment of a refrigerator. Upon freezing, to remove the ice block or cube, the container is grasped with one hand and the ring with another and relative rotation imparted to the container and ring, whereupon the ice block is turned in its freezing chamber, cams 12 or 20 assisting in the dislodging action.

It will be understood that certain limited changes in construction and design of the container and coacting ice-dislodging means may be made without departing from the scope of the invention as defined by the appended claims.

What is claimed is:

1. In combination with a container having a rounded freezing chamber, ice-dislodging means comprising an annular centrally open member rotatably mounted on the top of the container and carrying a fixed downwardly-projecting finger or stud to be embedded in the ice mass resulting from the freezing of a fluid in said chamber, said finger being eccentrically disposed with respect to the axis of the chamber whereby, when relative rotation is imparted to the container and said member, the ice mass is dislodged from said chamber.

2. In combination with a container having a rounded freezing chamber, ice-dislodging means comprising a ring having means rotatably supporting the ring on the top edge of the container, said ring being provided with a fixed downward-projecting finger to be frozen in the ice mass resulting from the freezing of a fluid in said chamber whereby, when the ring is rotated with respect to the container the ice mass is dislodged from said chamber, said ring being provided with a knurled outer surface and said container being provided with gripping means to facilitate relative rotation of the ring and container.

3. In combination with a container having a rounded freezing chamber, ice-dislodging means comprising a ring member having a downwardly projecting flange and a coacting radially inwardly projecting flange forming a bearing seat for the ring on the top edge of the container, a fixed finger secured in said inwardly projecting flange and extending downwardly into the chamber to be embedded in the ice mass during freezing of a fluid in said chamber, said finger being eccentric with respect to the vertical axis of the chamber whereby, when relative rotation is imparted to the container and ring, the ice mass is dislodged from said chamber.

4. In combination with a container having a

circular freezing chamber and a beaded edge at the top of the chamber, ice-dislodging means comprising a ring having a downwardly-projecting flange and a coacting radially inwardly projecting flange together defining a bearing seat for the ring on said beaded edge, the radially inwardly projecting flange of said ring being formed with an enlargement, a finger or stud fixed in said enlargement and projecting downwardly into said chamber to a point normally below the liquid level of the fluid to be frozen, the bottom wall of said container being formed with a cam member projecting upwardly into the chamber to facilitate dislodgment of the frozen mass when relative rotation is imparted to the ring and container.

5. In combination with a container having a rounded freezing chamber, ice-dislodging means comprising a ring having a downwardly projecting flange and a radially inwardly projecting flange together defining a bearing seat whereby the ring is rotatably supported on the top edge of the container, a fixed finger secured in said radially inwardly projecting flange and extending downwardly into said chamber to a point normally below the liquid level of the fluid to be frozen whereby, when relative rotation is imparted to the container and ring the frozen ice mass is dislodged from said chamber, the outer surface of said ring and container being provided with gripping means to facilitate such relative rotation.

6. In combination with a container having a rounded freezing chamber, ice-dislodging means comprising a ring having a downwardly projecting flange and a radially inwardly projecting flange together defining a bearing seat whereby the ring is rotatably supported on the top edge of the container, a fixed finger or stud secured in said radially inwardly projecting flange and extending downwardly into said chamber to a point normally below the liquid level of the fluid to be frozen whereby, when relative rotation is imparted to the container and ring the frozen ice mass is dislodged from said chamber, the outer surface of said ring and container being provided with frictional gripping means to facilitate such relative rotation, the gripping means for said container being in the form of a strip of roughened material cemented to the outer surface of said container and bearing indicia on a portion thereof.
